his Attorney

UNITED STATES PATENT OFFICE.

JAMES M. SLICKER, OF LOS ANGELES, CALIFORNIA, ASSIGNOR TO BARKER BROTHERS, INC., OF LOS ANGELES, CALIFORNIA, A CORPORATION OF CALIFORNIA.

MATTRESS.

Application filed July 1, 1922. Serial No. 572,179.

This invention relates to mattresses, pillows, pads and the like, or any similar form of stuffed objects; and a primary object of the invention is the production of a non-stretching article that will efficiently resist being stretched out of proper shape, and that can be easily, effectively and inexpensively manufactured.

For the purposes of this specification, I shall explain my invention as applied to a mattress, but without thereby limiting the invention particularly to a mattress. Also, I shall explain my invention as applied to prevent stretching—to prevent increase of dimension—in one direction only—the transverse direction across the mattress; but it will be readily understood that the invention may be applied to prevent stretching of a mattress, for instance, either longitudinally or transversely, or both.

The invention will be best understood from the following detailed description of a specific form of it applied to a mattress, reference for this purpose being had to the accompanying drawings, in which:

Fig. 1 is a plan view of a mattress equipped with my invention; Fig. 2 is an enlarged fragmentary section taken as indicated by line 2—2 on Fig. 1; and Fig. 3 is an enlarged fragmentary plan of a small portion of the mattress; and Fig. 4 is a detail section on line 4—4 of Fig. 3.

In the drawings I illustrate a mattress having upper and lower ticks 10 and 11, and side and end box-walls 12 and 13. These parts of the mattress may be secured together in any of the well known manners; and the mattress is tufted with vertical ties 14, in any of the well known manners, the ties extending between the top and bottom ticks 10 and 11 and terminating in buttons or knots, or any other suitable arrangement, as illustrated at 15.

Now, as is well known, a mattress of this kind and character, constructed without any arrangement to prevent stretching, will materially increase in dimensions when put into use, and will soon be larger than the bed for which it is intended, and will become loose and flabby. In practice, I find that the most objectional stretching of such a mattress takes place transversely. This stretching is due to the fact that the convex portion of the mattress ticks between the ties 14 become flattened; and is particularly

notable transversely on account of the stretching of the fabric itself in that direction more than lengthwise.

In order to prevent this condition arising, when the mattress is constructed I incorporate into its structure a plurality of stretch-resisting strips or bands 20 made of some suitably strong fabric, say something like a tape. These stretch-resisting bands extend preferably across the mattress in the lines of the ties, from the outermost tie at one side to the outermost tie at the other side. They do not extend clear to the side walls of the mattress. They are secured to the upper and lower tickings 10 and 11 only at points adjacent the ties, as by the stitching indicated at 21 in Fig. 3. Thus these stretch-resisting bands 20 are independent and free of the mattress tickings at all points excepting at the tie points; and being thus free and independent they may assume a straight line position, as indicated in Fig. 2. They are cut with the length of the goods, or along the warp, so they will not subsequently stretch when strain is applied to them lengthwise.

Now, when the mattress box is first made up, with these stretch-resisting bands in place, the bands and tickings are gaged in dimensions to correspond to the desired finished dimensions of the mattress. That is, for instance, if the finished mattress is to be about four feet by six feet, the tickings are originally cut about four feet four inches by six feet six inches; and if the finished distance from the edge of the mattress to the first row of tufts at each side is to be made six inches, then the actual length of each stretch-resisting band 20 between the two outermost tufts, will be made precisely three feet. (Of course the band from end to end is a little longer to provide room for stitching at its ends.)

When the mattress box, thus constructed is filled (before being tufted) the filling more or less presses the band 20 out against the upper and lower ticks 10 and 11; so that when the mattress is then tufted, the bands at first assume a position, between tufts, more or less like that indicated in dotted lines at 20^a in Fig. 2; but the bands will not, even during the stuffing, be pushed out of straight-line position as much as the ticks themselves, because the linear length of the bands between the two outermost rows of

tufting is less than the linear length of the tick between those two outermost rows of tufting. For instance, assuming again that the linear length of the band between the two outermost rows of tufting is three feet, then the linear length of the ticks between those two outermost rows of tufting is something over three feet, say three feet three inches, and the excess length of the tick is distributed between the successive tuft points where the band is sewed to the tick, so that, in every space between the point of attachment of the band to the tick there is a certain amount of fullness of the tick. This fullness provides for keeping the ticks in tufted condition even after the bands have straightened out true straight-line position. Also, the bands being narrow and the stuffing being in direct engagement with the inner faces of the two ticks on both sides of the band, and somewhat over the band as the filling works into the space between the band and the ticks, the ticks will at all times be pressed out in its proper tufted condition, while the band tends to assume a straight line. Furthermore, the bands tend to take a V-formation in section as illustrated in Fig. 4; allowing the stuffing more free access to the ticking. After a short use of the mattress, the bands assume their true straight-line position, the mattress stretching laterally very slightly, while the bands are so doing; then after the bands have so assumed their straight-line position, no further stretching of the mattress can take place. The relative positions of the bands and the ticking at that time are shown in Fig. 2.

The gathers, illustrated at 25, along the sides of the mattress are merely for the purpose of taking up the extra length of the ticks along their edges to correspond to the amount taken up in the central part by the tufting.

I have found, by actual use of mattresses constructed in accordance with this invention, that the mattress is perfectly constrained against stretching, against exceed-

ing its proper originally designed dimensions, and against stretching out of shape. A mattress constructed in this manner holds its body exceptionally well. Also, as will be readily seen, it is very easily constructed at very small additional cost as compared with an ordinary mattress; and furthermore it presents no difficulties or complications of filling. Furthermore, having two thicknesses of fabric at each ticking, one running lengthwise (the mattress tick) and one running crosswise (the bands), there is a great added strength resisting rupture, as for instance, splitting or tearing of the tick along its length. Thus I can cinch the tufts down more tightly and deeply and hold the filling more firmly against movement and stress the ticks to a smoother surface, all without danger of tearing the ticks. The filling is set more tightly under the ties and they do not pull out or "pop" out when the mattress is folded or rolled.

I claim:—

A stuffed article of the character described that embodies top and bottom tickings, a stuffing, and spaced lines of spaced ties by which the tickings are tufted, the outermost ties being spaced inwardly from the edge of the article, strain resisting bands at the inside face of each ticking extending along the lines of ties from the outermost tie at one side to the outermost tie at the opposite side only, each band being secured to the ticking at all the tie points in its corresponding line of ties and being otherwise unattached to the ticking, the width of the bands being small as compared with the distance between adjacent lines of ties and the linear length of the bands between ties being less than the linear length of the ticking between ties, all so that the stuffing may hold the ticking out in tufted formation while the bands are straight.

In witness that I claim the foregoing I have hereunto subscribed my name this 26th day of June 1922.

JAMES M. SLICKER.
